UNITED STATES PATENT OFFICE.

BENJAMIN J. BERGMAN, OF NEW YORK, N. Y.

THREAD-CONTROLLING DEVICE FOR SEWING-MACHINES.

SPECIFICATION forming part of Letters Patent No. 680,192, dated August 6, 1901.

Application filed April 24, 1900. Serial No. 14,099. (No model.)

To all whom it may concern:

Be it known that I, BENJAMIN J. BERGMAN, of New York, county and State of New York, have invented an Improvement in Thread-Controlling Devices for Sewing-Machines, of which the following description, in connection with the accompanying drawings, is a specification, like letters and figures on the drawings representing like parts.

5 The invention to be herein described is applicable more especially to buttonhole-sewing machines of the class represented in United States Patent No. 494,280, dated March 28, 1893.

10 In accordance with this invention I have applied to the rotating needle-bar a pull-off device and thread-guard, said device pulling off from the thread-supply a sufficient quantity of thread just as or before the button-

15 hole is completed, and the stitch-forming mechanism is stopped with its needle withdrawn from the work, said slack thread being freely supported by the guard and given up to the complementary stitch-forming mechanism coöperating with the eye-pointed needle when said needle is again started to make its first stitch in another buttonhole to be made. In the machine to be herein described, as provided for in the patent referred

20 to, the stitch-forming mechanism carried by a stitch-frame is started into operation at one end of the buttonhole and overedge stitches are made completely about the edge of the buttonhole, and the buttonhole having been

25 completed by a relative change of position of the stitch-frame and cloth-frame provided with the usual cloth-clamp the stitch-forming mechanism is put into its inoperative position or stopped with the needle elevated,

30 and thereafter while the stitch-forming mechanism is inoperative the relative positions of the stitch-frame and clamp-frame are changed to bring into its operative position the buttonhole-cutting mechanism, and in such position of the parts the machine is stopped.

35 The operator puts the material in which the new buttonhole is to be cut in the clamp and closes the clamp, which starts the machine, causing the cutter to descend and cut the

40 buttonhole. This is done at a high speed of the machine and the high speed is continued

until a change is effected in the relative positions of the stitch-frame and cloth-frame to put the stitch-forming mechanism in position to commence stitching a cut buttonhole, 55 all as in said patent. On the arrival of the stitch-forming mechanism in its position to be started the stitch-forming mechanism is started automatically into operation, and thereafter the slower speed of the machine 60 controls throughout the stitching of the buttonhole. Herein the needle-thread pulled off from the tension device and stored up during the stitching of the buttonhole about the eye and from the eye to the finished end is 65 freely supported by the thread-guard and given up to the stitch-forming mechanism at the first descent of the needle in commencing to stitch a new buttonhole, such giving up of the slack thread enabling the looper or 70 other device coöperating with the eye-pointed needle to unerringly engage and hold the needle-thread in the first stitch of the buttonhole.

75 My device in the form in which I have herein illustrated it consists, essentially, of an arm having thread-eyes and a collar and a thread-guard to freely support the thread, the collar being applied to the upper end of the rotatable needle-bar.

80 Figure 1 represents a top or plan view of a sufficient portion of a buttonhole-sewing machine to enable my invention to be understood. Fig. 2 is a detail showing a portion of the usual cloth-clamp. Fig. 3 is a partial 85 right-hand side view of the apparatus shown in Fig. 1. Fig. 4 is a diagrammatic view showing the top of the needle-bar and the tension device with the pull-off in different positions.

90 Referring to the drawings, *a* represents the overhanging arm of a stitch-frame. *a'* shows part of the clamp-frame; *b'*, the needle-bar; *b²*, the complete gear on the needle-bar; *b³*, an eye-pointed thread-carrying needle; *22*, 95 one of the levers of a cloth-clamp; *m'*, a clamping-foot of said lever; *23*, a pivot for the lever *22*; *b⁴*, a take-up; *b⁵*, a tension device for the needle-thread, it being acted upon by a spring *b⁶*, the force of which is controlled by 100 a nut *b⁶*. These devices are all common to the patent referred to. Coöperating with this

eye-pointed needle b^2 in the formation of over-edge stitches for buttonholes is in practice employed a complementary stitch-forming mechanism which may be an eye-pointed 5 looper or needle, such as provided for in said patent, and herein the stitch-forming mechanism will be actuated, as fully provided for in said patent, and the stitch-frame will carry, as provided for in that patent, buttonhole- 10 cutting mechanism actuated as provided for in said patent, and the stitch-frame in the operation of stitching a buttonhole will be run at one speed and after the buttonhole has been finished and the stitch-forming mechanism has been stopped, so that it no longer 15 stitches, a faster-speed mechanism will come into operation to impart a faster motion to the parts during the time that the relative positions of the stitch-frame and clamp-frame 20 are being changed to put the buttonhole-cutting mechanism into proper coöperative relation to the clamp that the latter may receive new material and the buttonhole be cut, and the stitch-frame and cloth-frame may then be 25 returned into a position to put the stitch-forming mechanism into position to be again started to commence the stitching of a new buttonhole.

I will now particularly describe my additions to the old parts herein alluded to.

As I have herein chosen to illustrate my invention the collar 10 of the arm 12, constituting one form of pull-off, is slipped over the end of the needle-bar b' and secured in 35 position thereon by a set-screw 13. The arm has, as shown, (see Fig. 3,) three thread-holes, through either of which may be passed the needle-thread 14 under the control of the take-up b^3 , the thread coming to the take-up from 40 a suitable tension device, as b^4 . The arm shown has two like thread-guards 16, which preferably extend lengthwise of the arm on one side thereof, being secured at or near the end of the arm and also at or near the collar. 45 This thread-guard extending lengthwise of the arm serves to freely support the slack thread after it is drawn from the thread-supply. The needle-thread from the take-up is led through one of the thread-holes in the 50 arm, and thence down through the hollow needle-bar b' out through an opening 17, common to said patent, at the lower end of said needle-bar, and through the eye of the needle b^2 .

55 Figs. 1 and 3 by full lines show the pull-off in the position it occupies when the stitch-frame and cloth-frame are in position to receive material that the cutter may act to cut the material. The dotted-line position, Fig. 60 1, is that occupied by the pull-off when the stitching of the buttonhole is to be commenced, the full-line position, Fig. 4, being that occupied by the pull-off as the stitching of the buttonhole is completed. Viewing 65 Fig. 1, the position designated by dotted lines is that occupied by the pull-off when the stitch-forming mechanism is about to be

started to commence the stitching of a buttonhole, and it will be seen that there is slack thread (designated by dotted lines) between the end of the pull-off and the take-up. This slack thread freely supported on the guard insures a plentiful supply of thread ready to be drawn easily through the eye of the needle when the needle-thread loop is entered by the complementary or understitch-forming device, so that with such slack thread stored up there is no possibility of the first stitch in making the buttonhole not being made properly.

During the operation of stitching the buttonhole the stitch-frame and cloth-frame have imparted to them relative movements at a predetermined speed, the stitch-forming mechanism making stitches along one side of the buttonhole about the eye thereof and then along the opposite side and finishing the buttonhole, and during this stitching of the buttonhole and finishing the same the pull-off rotates with the needle-bar and stops in the full-line position, Fig. 4, so that the needle-thread is made to occupy the position shown by the line 14—that is, it is led from the take-up or tension about the collar and along the side of the arm of the pull-off. In this position the needle-bar is lifted and the stitch-forming mechanism, the buttonhole having been completed, is stopped with the pull-off holding the thread taut. At this point the fast-speed driving mechanism for the stitch-frame, fully described in said patent, comes into operation and the stitch-frame is moved in the direction of the arrow 7, Fig. 1, causing the needle-thread to be bent over the finger 20 of the cloth-clamp, as represented in Fig. 3, the movement of the stitch-frame being continued until the usual buttonhole-cutter (not shown, but common to said patent) is put into operative position with relation to the open cloth-clamp. The cutting mechanism having been brought into operating position, the fast-speed motion is thrown out of operation and the stitch-frame is left stationary with the needle-bar yet elevated, and during this motion of the stitch-frame the usual sector for rotating the stitch-forming mechanism has turned the needle-bar b' , so that the pull-off occupies the position shown by full lines, Fig. 1, and as the cutting mechanism comes into position to have the material put into the clamp the pull-off has given up some slack thread which has been pulled through the needle by the action of the needle-thread between the point of the needle and the work against the finger 20. When

the pull-off occupies the full-line position, Fig. 1, the operator cuts the needle-thread close to the work, puts the new material in the open clamp, and closes the clamp. The closing of the clamp puts automatically into operation the usual fast-speed mechanism common to said patent, and by the time that the cutter begins to descend the pull-off occupies the position shown by dotted lines,

Fig. 4. The cutter operates quickly and rises and the fast-speed operating mechanism continues until the stitch-forming mechanism has been brought into its starting position, at which time the pull-off occupies the dotted-line position, Fig. 1. Viewing Fig. 1, it will be seen that the thread leads directly from the take-up to and through the eyes at the end of the pull-off and thence into the hollow needle-bar. The starting position of the pull-off when the first stroke of the needle is made in commencing to stitch a buttonhole leaves a considerable amount of slack thread sufficient to always insure that the under or complementary stitch-forming mechanism engage the loop of needle-thread and secure the needle-thread in the work. The stitch-forming mechanism is started while a slower speed is available for moving the stitch-frame, and during this stitching operation the pull-off moves from its dotted-line position, Fig. 1, into the full-line position, Fig. 4, said full-line position showing the position occupied by the pull-off and stitching mechanism when the last stitch of the buttonhole is completed, the stitching mechanism at the rise of the needle from the point where it made its last stitch in the buttonhole being suspended while the cutting operation takes place, as hereinbefore described.

Having described my invention, what I claim as new, and desire to secure by Letters Patent, is—

- 35 1. In a buttonhole-sewing machine, stitch-forming mechanism comprising a needle-bar, means to rotate said needle-bar, an attached pull-off having a thread-receiving hole near its end to receive the needle-thread on its way to the needle-bar, and an attached thread-guard extending lengthwise of the pull-off and on which the thread is adapted to be freely supported, the rotation of the needle-bar in stitching a buttonhole pulling off a supply of thread with which to commence the next buttonhole.
- 40 2. In a buttonhole-sewing machine, stitch-forming mechanism comprising a needle-bar, means for rotating said bar, an attached pull-off having a series of thread-receiving eyes near its end and a thread-guard connected to said pull-off, said guard extending length-

wise of the pull-off and on which the thread is adapted to be freely supported.

3. In a sewing-machine, a hollow needle-bar, means for rotating said bar, a connected eye-pointed needle, a pull-off composed of an arm and collar surrounding the needle-bar, the arm having a series of thread-passages to receive the thread on its way through the hollow needle-bar to the eye-pointed needle, means to connect said collar adjustably with the needle-bar, the side of the arm and the collar-sustaining thread at the completion of the stitching of a buttonhole which is given up at the commencement of the next button-hole.

4. A hollow needle-bar, a pull-off adjustably attached to said needle-bar and having a thread-receiving eye near its outer end to receive the thread preparatory to its passage through said needle-bar, and means to rotate said needle-bar during the stitching operation to draw off slack thread from the thread-supply during stitching and to give up said slack thread during a reverse movement of said needle-bar to put it in position to resume stitching of another buttonhole, and a thread-guard extending on one side of the pull-off and on which the thread is adapted to be supported.

5. In a sewing-machine, the combination with the stitch-forming mechanism comprising a needle-bar, of a pull-off axially adjustable on said needle-bar and having a series of thread eyes or passages for the thread located at different distances from the needle-bar and thread-guards connected to said pull-off and movable therewith and on which the thread is adapted to be freely supported.

6. In a sewing-machine, the combination with the stitch-forming mechanism comprising a needle-bar, of a pull-off carried by said needle-bar, and having a thread-eye, and thread-guards extending lengthwise of and above and below the pull-off between which the thread is adapted to be freely supported.

In testimony whereof I have signed my name to this specification in the presence of two subscribing witnesses.

BENJAMIN J. BERGMAN.
